Primary Examiner — Natasha Vujcic*Assistant Examiner* — Liv C Anderson(74) *Attorney, Agent, or Firm* — Ware, Fressola, Maguire & Barber LLP**CLAIM**

I claim the ornamental design for a bag light, as shown and described.

DESCRIPTION

FIG. 1 is a top perspective view of a bag light;

FIG. 2 is a top view thereof;

FIG. 3 is a bottom side view thereof;

FIG. 4 is a right side view thereof;

FIG. 5 is a left side view thereof;

FIG. 6 is a front side view thereof; and,

FIG. 7 is a back side view thereof.

The broken lines in the drawings depict portions of the bag light and form no part of the claimed design.
